UNITED STATES PATENT OFFICE.

CHARLES F. HESS, OF SCRANTON, PENNSYLVANIA.

COIN SORTING AND STACKING APPARATUS.

No. 834,805.

Specification of Letters Patent.

Patented Oct. 30, 1906.

Application filed September 25, 1905. Renewed October 5, 1906. Serial No. 337,628.

To all whom it may concern:

Be it known that I, CHARLES F. HESS, a citizen of the United States, residing at Scranton, in the county of Lackawanna and State of Pennsylvania; have invented certain new and useful Improvements in Coin Sorting and Stacking Apparatus; and I do hereby declare the following to be a full, clear, and exact description of the same, reference being had to the accompanying drawings, forming a part of this specification, and to the letters of reference marked thereon.

The present invention relates to the type of coin-handling apparatus forming the subject-matter of my contemporaneous application, Serial No. 245,091, filed February 10, 1905. In this present case features common to both applications are illustrated, but not described in detail, save where they constitute the subject-matter of claims.

The objects of the invention are to secure a more certain and uniform action, to effectually control the delivery of separated coins to the wrappers or receivers without interrupting the separating operation, and to simplify and improve the mechanical details of construction.

The present machine, like that of the application before referred to, embodies a series of superposed carriers, preferably one for each denomination of coin, and arranged in the relative order of the size of the coins to be handled—*i. e.*, with the carrier for the larger coins at the top, whereby smaller coins may pass freely down through the carriers until the carrier for that particular size coin is reached, the latter carrier being adapted to convey the coins to a mechanism for discharging them from the carrier. In the present case, however, instead of the coins being discharged directly into the receiver or wrapping-stack, as set forth in the other application, the coins are discharged into an intermediate holder or reservoir and are in turn discharged in succession from the reservoir into the stacks, whereby a more favorable opportunity is afforded for counting and automatically segregating the coins into piles or stacks each containing a predetermined number of coins without in any way interfering with the continuous operation of separating coins of different denominations.

Further details of the present invention

will be hereinafter described, and pointed out particularly in the appended claims.

Referring to the accompanying drawings, Figure 1 is an elevation, partly broken away and with duplicate parts omitted, of a coin-handling apparatus embodying the present improvements. Fig. 2 is a plan of the bottom section of the frame, showing the ball-bearing for supporting the several carriers, power-wheel, and shaft. Fig. 3 is a vertical section through the base-section with the power-wheel and driver in place. Fig. 4 is a bottom plan of the power-wheel. Fig. 5 is a top plan view of one of the carriers, showing the coin-receptacles and openings. Fig. 6 is a section on the line 6 6, Fig. 5, with part of the annular walls of the frame-section in dotted lines. Figs. 7 and 8 are a section and perspective view, respectively, of a part of the carrier. Fig. 9 is a perspective view of one of the frame-sections, the discharging mechanism for one carrier, and the brushes for distributing the coins on the carrier, parts of the frame being broken away. Fig. 10 is a detail section showing one of the brushes. Fig. 11 is a perspective view of the top section of the frame and the coin-hopper, parts being broken away. Fig. 12 is a perspective view of one of the stacks, reservoir, transferring and counting mechanism. Fig. 13 is a detail of the snail ratchet-wheel for supporting the coin-receivers in the stack. Fig. 14 is a vertical section of a part of the stack, the reservoir, and transfer-blade. Fig. 15 is a detail sectional elevation of the pawl mechanism for the snail-wheel and counting and transferring mechanism. Figs. 16 and 17 are elevations of a wrapper holder or receiver. Fig. 18 is an elevation of a holder or receiver with a wrapper in position therein. Fig. 19 is a view of a wrapper opened out flat. Fig. 20 is a sectional view showing a modified form of holder or receiver.

Similar letters of reference in the several figures indicate like parts.

The several sections of the casing are, as in the former apparatus, each formed by concentrically-arranged rings A A', and the sections are placed one above the other around a central shaft B, adapted to receive rotary motion through a power-wheel C, Figs. 3 and 4, preferably driven by a bevel gear and pinion c and a crank-shaft c'.

The weight of the shaft, carriers mounted thereon, and power-wheel is preferably carried on a ball-bearing D, which should be of large diameter to prevent lateral play at the upper end of the shaft to avoid as far as possible frictional contact between the carriers and frame.

Keyed to the shaft in position to underlie each of the frame-sections are carriers E, each having coin-pockets preferably in the form of radial recesses e, Figs. 5 to 8, adapted to receive and hold coins of the proper size to be handled by that carrier and each, save the lowermost one, having apertures e' for the passage therethrough of coins of smaller size than those adapted to be handled by the carrier. To overcome as far as possible liability of more than a single coin remaining in each pocket, the rear walls of the pockets only present a narrow ledge or are of less height than the thinnest coin to be handled, and the portions of the carrier intermediate the pockets are beveled or inclined, as shown at e² in Figs. 7 and 8. Inclined projections e³ extend into the apertures e' to prevent coins sticking therein, as in the prior apparatus.

The discharging mechanism of the present apparatus (see Fig. 9) consists of an arm or lever F, one for each carrier, pivoted within the frame-section and adapted to be advanced by a spring F'. The lever F has a coin-engaging blade f, adapted to pass successively through a slot in the inner end of each pocket or carrier, said slots, however, being too narrow to permit a coin to escape through the frame-ring. The discharge is retracted by inclines moving with the carrier and preferably taking the form of a ring G, secured to the carrier and having projections g on the inner side, with one face beveled or inclined to engage and retract the discharger, while the blade f projects through beneath the ring. The ring, in effect, constitutes the inner wall of the pockets.

Above the carriers is a distributing wheel or disk H, Fig. 11, secured to the shaft and having an upwardly-curved central part h, around which is arranged the outwardly-flared lower edge of receiving-hopper I. The hopper is stationary, but vertically adjustable by screws i to vary the width of the slot or opening between its lower edge and the distributing-disk. This slot should be of such width as to permit the largest coins to pass therethrough, but at the same time prevent the coins from passing *en masse* into the apparatus. Foreign articles will also be prevented from passing, and to this extent the distributor acts as a selector for the separating apparatus.

As the coins pass from the hopper out into the distributing-disk they are carried around and engage inclines i², by which they are swept off the edge of the distributor and into the first carrier of the separating mechanism.

To prevent the coins passing into the pocket at the discharging-point (f¹⁰, Fig. 9) or in immediate proximity thereto a fixed guard i is provided, extending partially around the distributor, and in addition over each carrier at the discharging-point is an inclined guard K, preferably pivotally mounted on the frame. These inclined guards are so arranged (see Fig. 1) that the lower end of one overlaps the upper end of the next lower one, and together they form a spiral incline, which should a small coin start at the top over one of the discharging mechanisms will deflect the same away from each discharging mechanism in turn until the proper carrier is reached, when the coin will be carried around through the larger part of a circle and presented to its non-discharging mechanism.

Brushes L are arranged over each carrier to cause the coins to enter the pockets or apertures properly, and for convenience these brushes may be of metal, each directly secured to a rod or support l, bent to form a crank at one end, and so as to pass easily through a bearing in the inner ring of the frame. The outer ends of the rods are held by screws, as l', journaled in the outer ring of the frame. Springs l², connecting the crank-arms and frame, serve to hold the free ends of the brushes down into proximity to the carriers.

By reference to Fig. 1 it will be seen that above the discharging-point of each carrier the frame is provided with a sight-opening closed by a glazed door M, whereby access may be had to relieve the apparatus in case a coin or foreign object lodges therein. From each discharge-aperture the coins pass into a reservoir or guide N, by which they are conducted down to the level of the power-wheel and in which if occasion demands the coins may accumulate before being finally discharged for stacking or wrapping. The upper ends of these reservoirs have inclined walls, as at n, Fig. 14, for deflecting the coins downwardly and preventing them from rebounding into the carrier. At their lower ends is a transfer mechanism for transferring the coins successively into the stacks or receivers and for indicating the value of coins transferred. This mechanism will be best understood by reference to Figs. 12 to 19, from which it will be seen that at one side of each reservoir N is a vertically-arranged guide N², in which the coins are stacked, and the coins are transferred successively from the reservoirs to the stacks by a transfer or pusher blade O, having its near end connected with one arm of a bell-crank lever O', the other end of which travels on the fluted or wavy edge (see Fig. 4) of the power-wheel C for imparting the necessary reciprocatory movements to the blade.

The blade is preferably retracted by a spring o in order that the transfer may be

interrupted by locking the blade forward, as will be presently described.

The escape of more than one coin at a time from the reservoir is prevented by a flexible brush O^2 , beneath which the blade travels.

In the preferred construction the coins are stacked directly in the wrappers, which latter are held in cylindrical form for the reception of the coins, and their ends are closed after their removal from the apparatus.

The construction of the wrappers and the receivers or wrapper-holders will be best understood from Figs. 16 to 20, and by reference to these figures it will be seen that the wrapper itself is primarily a flat sheet P of paper or flexible material, having a paster p along one edge, permitting it to be shipped flat and subsequently formed into a cylinder with the edges united. This construction also permits the same size wrapper to be used for different size coins, as the edges may be overlapped more or less in accordance with the size of cylinder desired.

The receivers or wrapper-holders each consists of a cylinder P' of metal, split longitudinally for the passage of one or both edges of the wrapper. This cylinder P' is mounted on a bar or support P^2 , having at one end a coin-supporting foot P^3 and at the other end a finger or projection P^4 , by which it is positioned and supported. The foot P^3 should properly occupy a position some little distance above the bottom of the wrapper, and for this purpose the wrapper may be notched or slotted, as at p' , or the rod P^2 may be bent down around the edge of the wrapper, as at p^2 in Fig. 20.

A number of the coin-wrappers and their holders may be placed in each of the guides N^2 one above the other, with the projections P^4 projecting through the slot in the front of the guides, and the alignment of the holders may be maintained by projections P^5 , adapted to embrace the edges of the slot in the guide N^2 .

It will be noted that the projections P^4 are located some distance above the top of the wrappers and will thus contact with the foot of the next higher wrapper-holder to space them apart and leave ample room for the entry of coins above each wrapper.

The movement of the wrappers and wrapper-holders through the guide N^2 is arrested by the projections P^4 coming into contact with and resting on the snail or spiral projection r on the rear face of the inclined escapement-wheel R .

Provision is made for moving the wheel a definite distance each time a coin is deposited in the wrapper, preferably consisting of a feeding-escapement operated by the coin as it is pushed from the reservoir to the wrapper or receiver.

In the embodiment illustrated the wheel R is provided with peripheral escapement-teeth r' . A pawl-carrier R' , pivoted at R^2 on a

fixed part of the frame, carries a vertically-movable pawl R^3 , held at the upward limit of its movement by a flat spring R^4 . On the end of the pawl-carrier is a holding-tooth s , and on the end of the pawl is an inclined operating-tooth s' , Figs. 12 and 15. With this construction the horizontal outward movement of the pawl-carrier and pawl will force the inclined tooth against one of the teeth r' and advance the wheel one step, and on the return movement the pawl rides down under the next tooth, while the holding-tooth moves into the space above the tooth r' , formerly engaged by the inclined tooth on the pawl, and holds the wheel in position.

A spring S' is provided for moving the pawl-carrier and pawl in one direction, and a projection S on the pawl-carrier, Fig. 15, projects into the path of the coin for moving the carrier outward as each coin is transferred from the reservoir to the wrapper or receiver. The coin is forced between the end of the projection S and the opposite side wall S^1 of its guideway by the blade O . The projection S is preferably cut away on the under side to overlie the blade O . Said blade is thin, and the coin projects above the same a sufficient distance to engage and operate the pawl-carrier, as shown clearly by the dotted lines in Fig. 15. The snail-cam, because of its inclination, projects into the path of the projection P^4 only at the top, and consequently when the cam has made one revolution the projection P^4 rides off the cam and drops clear of the lower portion of the cam.

To prevent any possibility of a coin being transferred during the time the receivers are being shifted or after one receiver has been dropped from the snail projection r and before another has reached its receiving position, a locking device operated by the receivers is provided for the transfer mechanism, whereby the latter is held inoperative during the shifting of the receivers. This locking mechanism consists, essentially, of a catch for holding the transfer-blade advanced and two latches operated by the receiver, one for moving the catch into operative position as a receiver is discharged from the snail projection on the control-wheel and the other for releasing the catch as the next receiver moves into position to receive the coins.

The catch is a simple pivoted detent T , the shoulder t of which is adapted to be moved down behind the blade to hold the same forward, as shown in Fig. 14. An arm T' on the detent is connected, through a rod T^2 , Fig. 12, with the rear end of a pivoted latch T^3 , Figs. 12 and 13, and the forward end of the latter projecting so as to intersect the path of the projections P^4 on the coin-receivers at a point below the snail projection r whenever the detent is elevated or out of operative position. With this construction a coin-receiver dropped from the snail

1 projection strikes the latch and throws the 5 detent down, so as to lock the blade, and the receiver cannot escape until the locking is effected, inasmuch as the latch cannot move out of the path of the projection P^4 until the 10 detent moves down, and the latter is supported by the blade until the blade is in position for locking. To again release the blade, a second latch T^4 is provided at such distance from the first that it will be moved only when the next receiver is in position. This second latch is shown below the first latch, and its rear end is connected with the forward end of the latch T^3 by a connecting rod T^5 , whereby 15 when one latch is in position the other is out of position to engage the projection P^4 , and vice versa.

The wheel R may itself be graduated to serve as a counter or indicator, or it may be 20 geared to any well-known form of counting mechanism for indicating the coins transferred to the receivers. Retrograde movement of the wheel R is prevented by a pawl V , and to reset the wheel, should this be desired, the pawl-carrier R' may be moved out 25 and the wheel advanced to the desired point.

In operation a suitable number of receivers are prepared with the wrappers therein, and when said wrappers are of light material 30 or do not present a properly-shaped opening at the upper end an expander W in the form of a small split ring may be inserted, as shown in Fig. 18. The prepared receivers and wrappers are placed in the guides one above 35 the other when the machine is ready for the reception of coins. The latter are dumped into the hopper and the shaft rotated, effecting the separation of the different denominations, as before described. As each loaded 40 wrapper and receiver is discharged from its guide the attendant takes the same, folds in the upper end of the wrapper, inverts and draws the same with its contained coin from the receiver, and folds in the opposite end. 45 The pasting of the edges of the wrapper may be done either at the time when it is placed in the receiver or when the wrapper and coin are withdrawn therefrom.

It will be noted that the inclined guards 50 separate the points of distribution and discharge of the coins. In other words, the coins are discharged at a point removed from any point at which the distribution to the carriers is effected, whereby smaller coins are 55 given ample opportunity to drop through to their own carriers, and in no case can a coin of smaller diameter be discharged from a carrier for coins of larger diameter.

Having now described my invention, what 60 I claim as new, and desire to secure by Letters Patent, is—

1. In an apparatus such as described, a superposed series of movable coin-carriers having coin-pockets therein and apertures 65 for the passage of coins of smaller diameter

than those to be held in the pockets, in combination with means for distributing coins to the pockets and apertures and means for discharging coins from the pockets in succession, the points of distance being located at points 70 removed from the points where the coins are distributed to the carriers; as set forth.

2. In an apparatus such as described, a superposed series of movable coin-carriers having coin-pockets therein and apertures 75 for the passage of coins of smaller diameter than those to be held in the pockets, means for distributing coins to said pockets and apertures, a discharging mechanism and a guard for preventing distribution of coins to 80 the carriers in proximity to the discharging-point; substantially as described.

3. In an apparatus such as described, a superposed series of coin-carriers having coin-pockets therein and apertures for the 85 passage of coins of smaller diameter than those to be held in the pockets, means for distributing coins to said pockets and apertures, a discharging mechanism and inclined guards overlying the discharging mechanism at the 90 discharging-points for deflecting the coins onto the carriers at points removed from the discharging mechanism; substantially as described.

4. In an apparatus such as described, a 95 superposed series of circular coin-carriers having coin-pockets and apertures for the passage of coins of smaller diameter than those to be held in the pockets, means for distributing coins to the carriers, means for discharging coins from the pockets and inclined deflectors over the discharging mechanism at the discharging-points, said deflectors being arranged in a spiral to successively direct the 100 coins until the proper carrier is reached; substantially as described.

5. In a coin-sorting apparatus the combination with a circular carrier having coin-pockets opening out at the periphery of the carrier, of a discharging mechanism embodying a pivoted spring-pressed lever carrying a discharging-blade adapted to enter the pockets in succession and means for withdrawing said blade intermediate the pockets; substantially as described.

6. In a coin-sorting apparatus, the combination with a circular rotary carrier having coin-pockets opening out at the periphery of the carrier, of a discharging mechanism embodying a pivoted spring-pressed lever carrying a discharging-blade adapted to enter the pockets in succession and inclines on the carrier coöperating with the lever for withdrawing the blade from the pockets; substantially as described.

7. In a coin-sorting apparatus, the combination with a circular rotary carrier having coin-pockets opening out at the periphery of the carrier and annular walls between which the coins are directed to the pockets, of a dis- 125

charging mechanism embodying a spring-pressed lever pivoted within the inner wall, a blade on said lever adapted to be projected outside of the inner wall and into the pockets in succession and inclines moving with the carrier for withdrawing the blade from the pockets; substantially as described.

8. In a coin-sorting machine, a coin-carrier having coin-pockets opening out at the periphery of the carrier, the portions of the carrier intermediate the pockets being inclined to form deflectors whereby when a pocket is occupied by a coin, other coins will be deflected into the succeeding pockets; substantially as described.

9. In a coin-sorting machine, a coin-carrier having coin-pockets opening out at the periphery of the carrier, one of the side walls of each pocket being of less height than the other and the portions of the carrier intermediate the pockets being inclined; substantially as described.

10. In a coin-sorting machine, the combination with the rotary carriers and the discharging mechanism, of a rotary distributing-wheel above the carriers, a coin-hopper spaced above the distributing-wheel and means for directing the coins beneath the edge of the hopper; substantially as described.

11. In a coin-sorting machine, the combination with the rotary carriers a vertical shaft on which they are mounted and a discharging mechanism for each carrier, of a horizontal distributing-wheel on the shaft above the carriers, a hopper spaced above said wheel and a projection within the hopper for directing the coins beneath the edge of the hopper; substantially as described.

12. In a coin-sorting machine, the combination with the superposed rotary carriers the discharging mechanism and rotary distributing-wheel above the carriers, of deflectors located in proximity to said distributing-wheel for directing the coins toward the periphery of the wheel; substantially as described.

13. In a coin-sorting machine, the combination with the superposed rotary carriers the discharging mechanism and rotary distributing-wheel above the carriers, of the peripheral guard extending partially around said wheel and the diagonal deflector located in proximity to the surface of said wheel for deflecting coins from said wheel at a point remote from the guard; substantially as described.

14. In a coin-sorting machine the combination with the apertured carriers and discharging mechanism for each carrier, of the receivers and mechanically-operated transferring mechanism for transferring the discharged coins to the receivers; substantially as described.

15. In a coin-sorting machine the combination with the apertured carriers and dis-

charging mechanism for each carrier, of the coin-receivers and a reciprocatory transfer-blade for transferring the discharged coins to the receivers; substantially as described.

16. In a coin-sorting machine, the combination with the apertured carriers and discharging mechanism for each carrier, of the coin-receivers, a transferring mechanism for transferring the discharged coins to the receivers and a lock for the transferring mechanism, controlled by the receivers; substantially as described.

17. In a coin-sorting machine, the combination with the apertured carriers and discharging mechanism for each carrier of coin-receivers, a transferring mechanism embodying a reciprocatory blade, a lock for holding said blade in inoperative position, and lock-operating devices controlled by the receivers; substantially as described.

18. In a coin-sorting machine, the combination with the apertured carriers, discharging mechanism for each carrier and reservoirs into which the discharged coins pass, of receivers and transferring mechanism for transferring the coins singly from the reservoirs to the receivers; substantially as described.

19. In a coin-sorting machine, the combination with the apertured carriers, discharging mechanism for each carrier and reservoirs into which the discharged coins pass, of receivers for the coins, a transferring mechanism for transferring the coins singly from the reservoirs to the receivers and a lock for said transferring mechanism, controlled by the receivers; substantially as described.

20. In a coin-sorting machine the combination with the apertured carriers, discharging mechanism for each carrier and reservoirs into which the discharged coins pass, of receivers for the coins, a transferring mechanism for transferring the coins from the reservoirs to the receivers embodying a reciprocatory blade, a lock for holding the blade inoperative and lock-operating devices controlled by the receivers; substantially as described.

21. A coin-sorting machine embodying means for separating coins according to their diameters, coin-receivers, guides for the receivers, a wheel having a snail projection thereon for supporting the receivers and mechanism for moving said wheel, itself controlled by the coins entering the receivers; substantially as described.

22. A coin-sorting machine embodying means for separating coins according to their diameters, coin-receivers, guides for the receivers, a wheel having a snail projection thereon for supporting the receivers, a pawl mechanism operated by the coins for controlling said wheel and means for singly advancing the coins to the receivers; substantially as described.

23. In coin-sorting mechanism a receiver for sorted coins embodying a cylindrical body, and a support for said body at one side of, and rigid therewith and having a coin-supporting foot at the lower end; substantially as described.
24. In coin-sorting mechanism, a receiver for sorted coins embodying a cylindrical body split vertically to hold a wrapper and a support for said body at one side of and rigid therewith and having a coin-supporting foot at the lower end of the cylindrical body; substantially as described.
25. In coin-sorting mechanism a receiver for sorted coins embodying a cylindrical body split vertically for holding a wrapper and having a coin-supporting foot rigid therewith and in line with the cylindrical opening through the body; substantially as described.
26. In coin-sorting mechanism, a receiver for sorted coins embodying a cylindrical body having a coin-supporting foot, a wrapper confined in said body and having ends for folding projecting beyond both ends of said cylindrical body and beyond the foot; substantially as described.
27. In coin-sorting mechanism a rotary carrier having coin-pockets and means for discharging coins from the pockets in combination with brushes for distributing coins to the pockets having crank-arms connected rigidly therewith and removable screws forming one journal for the brushes; substantially as described.
28. In a coin-sorting machine, the combination with a series of superposed carriers having pockets and coin-discharging mechanism for each carrier, of coin-receivers, transferring mechanism one for transferring the discharged coins of each carrier and a common operating-wheel for operating all the transferring mechanisms; substantially as described.
